RENEWABLE FUSE

Filed August 29, 1921

FIG. 1.

FIG. 2.

FIG. 3.

FIG. 4. FIG. 5. FIG. 6. FIG. 7.

FIG. 8.

INVENTOR

George R. Trumbull,

BY

ATTORNEYS.

UNITED STATES PATENT OFFICE.

GEORGE R. TRUMBULL, OF BANTAM, CONNECTICUT.

RENEWABLE FUSE.

Application filed August 29, 1921. Serial No. 496,322.

To all whom it may concern:

Be it known that I, GEORGE R. TRUMBULL, a citizen of the United States of America, residing at Bantam, Litchfield County, Connecticut, have invented a new and useful 5 Renewable Fuse, of which the following is a specification.

My invention relates to a renewable fuse and is in some respects similar to the invention disclosed in my co-pending application, Serial No. 495,030, filed August 24, 1921.

Ordinary renewable fuses may be readily overloaded by simply substituting for the 15 fuse link intended to be used a strip of metal of greater current carrying capacity. When a fuse blows, a great amount of heat is generated and the fuse link is often partially vaporized, and this vapor added to the 20 heated air in the fuse causes great pressure within the fuse which cannot be absorbed quickly by the body of the fuse which is usually of insulating material.

It is an object of my invention to provide 25 novel means for rendering the overloading of renewable fuses very difficult or practically impossible.

It is a further object to provide novel 30 means for preventing to some extent the generation of high pressures within the fuse body.

It is a further object to provide a novel 35 indicator for renewable fuses.

Other objects and features of invention 40 will be apparent as the specification proceeds.

Briefly stated in the preferred form of 45 my invention, there is provided a fuse body usually of insulating material and a fuse link extends through the body and is suitably secured at the ends. Within the body are positioned one or more metallic guard washers. Between the guard washers (when two are provided) is usually positioned 50 a metallic indicator. The guard washer and indicator are so formed as to permit the passage of the fuse link through the body. The fuse link in the preferred form is of irregular transverse cross-section for at least a portion of its length, and the 55 passages in one or more of the parts through which the link passes is preferably made to conform in shape substantially to the cross-

section of the irregular portion of the fuse link. 55

In the drawings, I have shown for illustrative purposes only a preferred embodiment of the invention.

Fig. 1 is a longitudinal sectional view of 60 a fuse embodying features of my invention.

Fig. 2 is a detail perspective view of one 65 form of fuse link suitable for my invention.

Fig. 3 is a detail perspective view of two 70 guard washers and an indicating member separated from the fuse body and from each other.

Fig. 4 is an end view of a baffle at one 75 end of the fuse.

Fig. 5 is a similar view of the same baffle 80 shown in Fig. 4 but viewed from the reverse side.

Fig. 6 is an end view of an end cap at 85 one end of the fuse.

Fig. 7 is a similar view of an end cap at 90 the other end of the fuse.

Fig. 8 is a fragmentary section of a detail. 95

In said drawings, the body of the fuse which is usually of insulating material is indicated at 10. In the form shown, the body has screw threaded thereon the end caps 11-12, preferably of hardened steel, each cap having passages 13-14 for the 100 fuse link 15. Cover caps 16-17 have been shown in screw threaded engagement with the end caps 11-12. The ends of the fuse link are preferably held between the cover caps, and in the form shown I have disclosed baffles 18-19 between the caps at each end of the body. These baffles it will be noted are slightly spaced from the cover caps as indicated at 20 to permit the passage 105 of gases generated when the fuse is blown.

The fuse link as herein disclosed is provided with a part intermediate its ends of reduced cross-section in order to cause the fuse to rupture at this point. At least a part of the fuse is of irregular transverse 110 cross-section and the specific fuse link shown is corrugated as best illustrated at 21 in Fig. 2. The opposite end of the fuse link may be a plain flat strip, and the extreme end may extend to the outside of the body 115 and bear a legend (not shown) to indicate

the current carrying capacity of the fuse. In the form shown, the baffle 18 is provided with a corrugated seat or plateau 22 conforming substantially in shape to the corrugated or irregular shaped end of the fuse. This is a precaution taken to insure the proper contact between the fuse and the corresponding cover cap or ferrule. In the present instance, the passage 14 in one end cap has been shown of a shape substantially conforming to that of the irregular shaped fuse link.

In the fuse herein illustrated, the cover caps or ferrules are usually passed between 15 clips on the fuse board to connect the fuse link in circuit. It should be understood that the ferrule type has been shown merely for the sake of illustration and I do not of course wish to be limited to that type of 20 contact since others are well known in the art. Much of the matter so far described has been shown in my co-pending application hereinbefore referred to.

Within the body is provided a novel type 25 of indicator and novel means for forming a passage for the fuse link. The indicator preferably comprises a movable block 25 of metal, preferably steel. In the form shown, the block has a passage 26 for the 30 passage of the fuse link. The stem 27 is preferably square and passes through a correspondingly shaped aperture in the fuse body and a spring 28 is provided for urging the indicator in one direction. The projecting end of the stem 27 is preferably covered 35 with or housed in insulating material 29 in order to avoid the possibility of shock when handling or touching the fuse when in circuit. The body of the indicator or the 40 insulating cover 29 preferably projects transversely slightly so as to completely cover the aperture in the body when the fuse is blown and the indicator forced upwardly. Such a construction will prevent 45 the escape of flame through the aperture provided for the stem.

Inside the body and preferably close to the indicator there may be provided one or 50 more guard washers 30-31. These washers are preferably stamped out of spring steel and after being pressed into shape are given a spring temper. Spring arms 32 are preferably formed on the washers, and if desired, feet 33 may likewise be formed 55 thereon.

The overall dimension of the washers is 60 preferably greater than the inside dimension of the fuse body so that when a washer is slid into the fuse body the spring arms will flex slightly to permit the introduction of the washer from one end, but if an attempt is made to withdraw the washer from the same end, the spring arms will dig into the body of the fuse and thus prevent the withdrawal of the washer. In Fig. 1 I have

shown two such washers applied to the fuse body, one being forced in from each end, and the indicator is confined between the two washers. It will thus be seen that once the indicator and washers are in place, neither the indicator nor the washers can be withdrawn. It will likewise be evident that no pins or securing means other than the spring arms are necessary for holding the guard washers in place. The washers have suitable passages 34 for the passage of the fuse link, and in the form shown, at least one of these washers is provided with a passage conforming substantially in shape to the irregular portion of the fuse link.

If found desirable or necessary washers 35 of insulating material may be interposed between each of the metallic guard washers and the ends of the fuse body, to prevent 75 arcing.

When the fuse blows the rupture usually 80 occurs between the ends of the link and in the vicinity of the indicator. The indicator immediately rises, due to the force of the spring and the pressure of gases within the body. The slight shoulder or projection on the indicator effectively seals the opening 85 for the stem 27 and prevents the passage of flame. The metallic parts within the fuse, such as the metallic indicator and the metallic guard washers, are good conductors 90 of heat, and immediately upon the blowing of the fuse these metallic parts absorb or conduct away much of the heat, and thus the gases within the body are not expanded to so great an extent and the pressure within the fuse will be materially less than without these metallic parts.

When the fuse blows the gases generated 95 or expanded escape through the apertures 38 in the end caps and, by passing around the baffles 18, 19, finally reach the apertures 39 in the cover caps and escape. The 100 gases, in traversing the tortuous path indicated, have their temperature reduced and the flame is dissipated before reaching the exterior of the fuse.

The provision of an opening of irregular 105 shape in one of the guard washers is an effective means for preventing the overloading 110 of the fuse by the substitution of a plain, flat or round strip. Since the guard washer is within the body of the fuse, access thereto is difficult and, as above described, the washer cannot be withdrawn.

In Fig. 8 is shown the end cap 11 applied 115 to the body 10. A pin 36 preferably of hardened steel is passed longitudinally through the end cap 11 and longitudinally into the body 10. The end of the pin is afterwards ground flush with the surface of the end cap and it is thus impossible to withdraw the pin, and so long as the pin is in position, the end cap cannot be unscrewed. A pivot 120 pin 37 for the baffle 18 by frictional engage- 125

ment with the tube 10 may likewise tend to hold the end cap against unscrewing.

While I have described in detail a specific form of the invention, I wish it understood that various changes may be made without departing from the spirit and scope of the invention as defined in the appended claims.

I claim:

1. In a fuse, a fuse body having end caps thereon with passages for a fuse link, a metallic guard washer within said body and removed a substantial distance from the ends thereof and having a passage for a link, said guard washer having angularly bent spring

arms for holding the same within the body, a fuse link extending through the passages and means for making contact with the fuse link at the ends of the body.

2. In a fuse, a fuse body, a pair of guard washers in said body each having an angularly bent spring portion for holding the latter in place, said washers being positioned in proximity to each other and removed from the ends of the fuse body and having passages therethrough for a fuse link, and means for making electrical contact with said fuse link at the ends of the body.

3. In a fuse, a fuse body and a fuse link therein, a guard washer having a holding arm extending at an angle thereto for securing the same in the body, an indicating member observable from the outside of the fuse body, said indicating member being positioned adjacent to so as to be guided by said guard washer, said guard washer and indicating member having passages therethrough for the fuse link.

4. In a fuse, a fuse body and a fuse link therein, an indicating member within the body and observable from the outside thereof, a separate guard washer within the body at each side of said indicating member, said guard washers being positioned adjacent to so as to act as guides for said indicating member, said indicating member and guard washers having passages for the fuse link.

5. In a fuse, a fuse body and a fuse link therein, a pair of guard washers within said body, one of said washers having a foot thereon for spacing the washers apart, said washers having passages for the fuse link.

6. In a fuse, a fuse body and a fuse link therein, a metallic guard washer within said body and having an arm for holding the washer in place, said fuse link having a part thereof of irregular cross-section and said washer having a passage for the fuse link and conforming substantially in shape thereto, said fuse link extending through and beyond said passage and being secured to said fuse body independently of said guard washer.

7. In a fuse, a fuse body and a fuse link therein, a pair of guard washers in the body and having spring arms for positioning the

latter, one of said washers having feet thereon for spacing the washers apart, said washers having passages therein for the fuse link.

8. In a fuse, a fuse body, end caps on said body and having fuse link passages therein, one of said end caps being of hardened steel and the passage therein being of predetermined irregular shape, a fuse link in said fuse body and extending through said passages and secured outside of said end caps, a part of said fuse link being of substantially the same irregular form as one of said passages.

9. In a fuse, a fuse body and a fuse link therein, a pair of metallic guard washers in said body, a metallic indicator within said body and in proximity to and between said guard washers, said metal indicator having a head of insulating material observable from the outside of the body.

10. In a fuse, a fuse body and a fuse link therein, a pair of metallic guard washers held in said body, a metallic indicator within said body and between said washers and guided thereby, said washers and indicator having passages for the fuse link.

11. In a fuse, a fuse body and a fuse link therein, a metallic guard washer in said body and having spring arms extending therefrom at an angle thereto whereby the washer may be forced into the body from one end and will be prevented by said spring arms from being withdrawn from the same end.

12. In a fuse, a fuse body having end caps thereon and having passages for a fuse link, a pair of cover caps for said body, a fuse link within the body and with the ends held between said caps at each end of the body, a pair of metallic guard washers in said body and spaced apart from each other, a metallic spring pressed indicator within said body and adjacent to and between said washers, said indicator having a head of insulating material observable from the outside of said body, said washers and indicator having passages for the fuse link.

13. In a fuse, a fuse body and a fuse link therein, a metallic washer within said body and having a passage for the fuse link and an insulating washer within said body and interposed between said metallic washer and one end of the fuse body to prevent arcing between the washer and said end of the fuse.

14. As an article of manufacture, a guard washer for a fuse comprising a metallic plate having a spring arm thereon and extending at an angle thereto, said washer having a passage therethrough.

15. As an article of manufacture, a guard washer for a fuse comprising a metallic plate of spring steel having a pair of spring arms extending therefrom at an angle thereto, said washer having a passage therethrough.

16. As an article of manufacture, a guard washer for a fuse comprising a metallic plate having a spring arm thereon, a foot thereon and having a passage therein.
17. In a fuse, a fuse body, a hardened steel washer in said fuse body and having a passage therein of predetermined irregular shape, a fuse link in said body and extending through said passage of irregular shape, at least a part of said fuse being of predetermined irregular transverse cross section corresponding in shape to said passage so as to fit the same, and means for securing the ends of said fuse beyond said passage to contact members.

GEORGE R. TRUMBULL.
